UNITED STATES PATENT OFFICE.

WILFRED SHURTLEFF, OF MOLINE, ILLINOIS, ASSIGNOR TO THE HERMAN NELSON CORPORATION, OF MOLINE, ILLINOIS, A CORPORATION OF ILLINOIS.

CONTROLLING DEVICE FOR RADIATORS.

Application filed July 2, 1923. Serial No. 649,097.

To all whom it may concern:

Be it known that I, WILFRED SHURTLEFF, a citizen of the United States, and a resident of Moline, in the county of Rock Island and State of Illinois, have invented new and useful Improvements in Controlling Devices for Radiators, of which the following is a specification.

This invention relates to improvements in controlling devices for radiators and more particularly to means for automatically regulating the delivery of the heating fluid to the radiator, and governed by the conditions existing at a given point within the radiator.

The object of the invention is to provide a device that will control the fluid supply at the inlet end of the radiator and prevent the loss of heat that ordinarily is dissipated in the return pipes, and to otherwise control the temperature or heat radiation under conditions of varying pressures of the fluid or steam supply.

The problem of controlling the heating capacity of a radiator by the hand operated valve is rendered uncertain, due to the fact that in the average steam or vapor heating plant it is difficult to maintain the steam pressure uniform. The same is true in a hot water heating plant. This condition is obviously the result of variations in the firing of the boiler and the draft. As a result, an excessive amount of heating fluid is delivered to a radiator, the excess being discharged into the return pipe and its heat dissipated as lost or ineffective.

In the accompanying drawings, a preferred embodiment of the invention is disclosed, wherein—

Figure 1 is a view in vertical section of a radiator with the controlling device installed,

Figure 2 is an enlarged detail view of the device in longitudinal section showing its internal construction,

Figure 3 is a cross-sectional view taken on line 3, 3 of Figure 2,

Figure 4 is a view in vertical section of a radiator showing a modified form of the device applied thereto,

Figure 5 is an enlarged detail view showing the method of regulation, and

Figure 6 is a cross-sectional view taken on line 6, 6 of Figure 5.

Referring to Figure 1, a typical form of radiator is shown, consisting of a plurality of sections 1, connected together at top and bottom by short sleeves or bushings 2, forming passages between the sections. Connected at the lower end of the right-hand end section is a supply pipe 3 having the usual hand-controlled valve 3^a, and at a corresponding point of the left-hand end section is a return pipe 4, also provided with a valve 4^a. Reducing fittings or bushings 5 and 6 are preferably inserted into the threaded openings formed in the end sections, and take the threaded ends of the supply and return valves 3^a and 4^a, respectively.

As clearly shown in Figure 1, the controlling device 7 is supported in the lower portion of the radiator and extends from the supply pipe connections, inwardly therefrom and transversely through the connecting passages of several of the radiator sections, the inner end terminating adjacent the lower end of the further or left end section, although, as will be presently pointed out, it is only essential that the free end of the device terminate beyond the first section, counting from the inlet end.

The control device consists of a tube or cylindric casing 7 which is supported at one end in a bushing 5 by means of an externally threaded end portion 8, having an internally threaded socket into which is screwed the end of the steam supply valve 3^a. At the inner end of the end portion 8 is screwed a valve seat 9 with an orifice 9^a opening into a chamber 10 having a plurality of radially opening ports 11 in its surrounding wall. These ports communicate directly with the lower portion of the first or right end section of the radiator.

Beyond the chamber 10 the tube is closed except near its free end where are formed another series of radial openings 12. Extending concentrically of the tube 7 is a rod or valve stem 13 carrying at its outer end a valve member 14 adapted in the axial movement of the valve stem to open and close the orifice 9^a. The opposite end of the valve stem extends endwise into a cylinder 15 which is screwed into the inner or free end of the tube 7, and closed by means of a screw plug 16. The wall of the cylinder is spaced from the wall of the tube. Thus

communication is established through the ports 12, 12 between the space surrounding the cylinder 15 and the interior of the radiator section in which the end portion of the tube is housed.

The cylinder terminates substantially at the midpoint of the tube 7, in what may be termed a head 15^a through which the valve stem extends. A quantity of packing 10 17 fills the remaining space from the head of the cylinder to the chamber 10, thereby preventing the passage of the heating fluid lengthwise of the tube.

At the end of the valve stem 13 is a cylindrical head or piston 18. The cylinder contains a quantity of liquid which acts to force the plunger forward when the liquid expands under a rise in temperature, thus seating the valve 13^a upon its seat and closing 20 the orifice 9^a. A bellows 19 of thin metal connects the piston 18 with the forward end or head of the cylinder 15, allowing movement of the piston without leakage of the liquid. Thus, as the liquid is cooled 25 and contracts, the piston is moved in a direction to open the orifice 9^a.

Mounted upon the exterior of the tube 7 is a circular plate or collar 20 capable of sliding endwise thereon. This plate 30 occupies a position adjacent the head end of the tube and beyond the ports 11. About the periphery of the plate 20 is a facing ring of some suitable porous material, its purpose being presently set forth.

35 As clearly shown in Figure 1, the plate 20 bears laterally against the end of the connecting passage between the end section and the adjacent or second section, thereby closing or sealing the same to the passage 40 of steam. In order that a positive sealing may be secured, a coil spring 22 surrounds the casing 7 between the plate 20 and the bushing 5 and serves to yieldingly force the plate against the end of the passage. 45 The purpose of the porous ring 21 is to allow the water of condensation to seep through into the sections beyond the sealing ring, thus preventing the accumulation 50 of condensation in the lower portions of the first section.

In setting forth the mode of operation of the device it may be assumed that the radiator is completely shut off by means of the valve 3^a in the supply pipe. The 55 radiator is therefore cold and partially filled with air. The steam is then turned on and flows through the orifice 9^a which, being restricted, admits the steam at a reduced pressure and velocity and in this condition the steam may be termed "vapor" to 60 distinguish it from the steam at the pressure at which it is supplied to the radiator.

The vapor thus enters the chamber 10 and escapes through the ports 11 into the surrounding space at the lower end of the first

section. Inasmuch as the plate 20 seals the passage from the lower end of the first section to the sections beyond, the vapor rises in the first section and expands until it dissipates the kinetic energy, and then distributes itself laterally throughout the upper portion of the several sections in strata or layers of uniform depth without turbulence. Thus the upper part of the entire radiator is heated uniformly. As the vapor continues to flow into the first section, the upper layer moves downwardly, gradually becoming condensed as the walls absorb the heat, and the water of condensation trickling down the sides and accumulating at the base of the sections. Thus the vapor disposes itself into several strata, gradually cooling as they advance downwardly driving the trapped air ahead and into the return pipe. After a period of time the vapor strata will reach the base of the sections, and surround the tube 7, the heat being transmitted to the walls of the cylinder 15, and thence to the liquid therein, thus closing the valve as herein-before described.

As the heat is dissipated from the radiator and the tube cools, the thermostatic element will contract, unseating the valve member and again admitting steam to the 95 radiator.

In this manner the admission of steam is automatically controlled, regardless of the pressure of the steam supply, and the setting of the valve in the supply pipe.

100 In Figures 4 to 6, a modified form of control device is shown, and comprises an addition to the parts already described. This added feature may be described as an external endwise shiftable sleeve 23 surrounding the tube 7, the latter together with the associated parts performing the same functions as heretofore, and therefore need not be again described.

105 The sleeve 23 extends substantially the full length of the tube 7, and, with the exception of the outer or right-hand extremity of the sleeve, a passage is formed between the tube 7 and sleeve 23. The extremity of the sleeve adjacent the inlet ports 11, 11 of the tube is reduced in diameter, as at 24, to provide a ring having sliding fit on the tube.

Extending axially from the upper edge of the sleeve 23 is an integral arm 25 to which is connected a rod 26 extending through the screw fitting 5 and terminating exterior of the radiator in an upturned handle 26^a. The handle is operated by hand to shift the sleeve axially and substantially a distance 125 equal to the longitudinal dimensions of the ports 11 in the chamber 10 of the tube 7. By shifting the sleeve in either direction, the reduced end portion 24 of the sleeve 130 covers or uncovers the ports 11 with the fol-

lowing results. Considering the sleeve to be shifted into the position shown in Figure 5, it will be observed that one-half of the area of the ports 11 is closed, with the 5 result that the volume of steam delivered to the first section of the radiator is reduced to one half. At the same time a portion of the ports 11 is open to the annular space between the sleeve 23 and the tube 7 beyond 10 the ring 24, so that a part of the steam is free to escape directly toward the free end of the tube 7. Thus it is seen that a bypassing of the steam is accomplished, to the end that the thermostatic element in the 15 tube becomes active to close the valve before the steam completely fills the radiator sections from the top. Thus the radiator may be operated at less than full capacity, namely, one-half the upper half being hot and 20 the lower half cold, thereby providing for a more economic operation in mild weather.

Similarly, by shifting the sleeve in either direction from the central portion, proportionately greater or less volume of steam is 25 by-passed from the first section directly to the sensitive end of the tube, affecting a shorter or longer delay in the action of the valve member with a correspondingly less or greater effective heating area of the radiator. 30

As already suggested, the device herein disclosed, and in either form, may be readily installed in any radiator, and provides an accurate and effective method of automatically controlling the heating capacity of a radiator.

Having disclosed a preferred embodiment of my invention, I claim—

1. In a device of the character described, 40 the combination with a radiator consisting of sections connected at their ends, and having a fluid inlet connected with one of the end sections, of a casing adapted to be mounted in said inlet and comprising a valve for controlling the fluid supply to the radiator, a temperature responsive element remote from said valve and operatively connected therewith, and a plate adjustably mounted on said casing intermediate said valve and heat responsive element.

2. In a device of the character described, 45 the combination with a radiator consisting of sections connected at their ends, and having a fluid inlet connected with one of the end sections, of a casing adapted to be mounted in said inlet and comprising a valve in said inlet, a chamber beyond said valve and communicating with the immediate section, a temperature responsive element remote from said chamber and operatively connected with said valve, and a plate adjustably mounted on said casing intermediate said chamber and said heat responsive element.

3. In an automatic fluid control device,

the combination of a radiator comprising sections connected at their opposite ends and having a fluid supply connection with one of said sections, a tubular casing extending from said inlet connection through passages 70 connecting the ends of said sections adjacent said inlet connection, a fluid inlet valve at one end of said casing, a temperature responsive element at the other end of said casing, and a plate adjustably mounted on 75 said casing intermediate the ends thereof and adapted to seal the passage from said first mentioned section and the remaining sections.

4. In an automatic fluid control device, 80 the combination of a radiator consisting of sections connected together by passages at their upper and lower ends and provided with fluid inlet and discharge connections in the opposite end sections and in alignment with said passages at the lower end of said section, a tubular casing adapted to be mounted in the fluid supply connection, a valve mounted in said casing for controlling the fluid inlet to said radiator, a temperature responsive element located at the opposite end of said casing, and an annular plate slidably mounted on said casing intermediate the ends thereof. 85

5. In a device of the character described, 90 the combination of a radiator having a fluid supply connection, a tubular casing mounted at said supply connection, a valve for controlling the fluid supply through a port in said casing, a thermostatic element in 95 said casing, and a member slidably on said casing and adjustable to regulate the flow of fluid from said port directly to said thermostatic element. 100

6. In an automatic fluid control device 105 for radiators the combination of a radiator, a casing adapted to be mounted in said radiator at the fluid inlet thereto, a valve for controlling the fluid supply into said radiator, temperature actuated means for operating said valve, said casing being provided with ports adjacent said valve, a sleeve slidable lengthwise of said casing and forming a longitudinal passage surrounding the same, said sleeve having a 110 reduced portion coacting with said port to direct a portion of the fluid through said passage, and means for sealing the interior of the radiator against the passage of steam lengthwise of said casing and exterior of 115 said sleeve. 120

7. In an automatic fluid control device 125 for radiators the combination of a radiator, a casing adapted to be mounted in said radiator at the fluid inlet thereto, a valve for controlling the fluid supply into said radiator, temperature actuated means for operating said valve, said casing provided with ports adjacent said valve, a sleeve slidable lengthwise of said casing and forming a 130

longitudinal passage surrounding the same, said sleeve having a reduced portion coacting with said port to direct a portion of the fluid through said passage, and means carried by said sleeve and engaging the interior of said radiator to prevent the passage of fluid along the exterior of said sleeve.

8. In a device of the character described, the combination of a radiator comprising a plurality of sections connected by passages at their upper and lower ends, a fluid supply pipe communicating with the lower end of one end section of said radiator, a tubular casing mounted in said supply connection and extended transversely into a section beyond said end section, a valve mounted in said casing and controlling the fluid supply to a chamber formed at the adjacent end of said casing, said chamber being provided with ports communicating with said end section, a thermostatic element operatively connected with said valve, a sleeve surrounding said casing and forming a passage extending substantially the length thereof, said sleeve having a reduced end portion coacting with said ports to direct a portion of the fluid through said passage, and a plate mounted on said sleeve adjacent said port

and adapted to close the passage from the lower end of said end section.

9. In a fluid control device the combination of a radiator having a fluid supply thereto, a valve controlling said fluid supply, a thermostatic element operatively connected with said valve, and located in said radiator remote from said inlet and normally subject to the temperature of the fluid adjacent thereto, and means for conducting all or a part of the fluid directly from said valve to said thermostatic element.

10. In a fluid control device, the combination of a sectional radiator having a fluid inlet to one section, and a fluid outlet from another section thereof, a valve in said inlet, a thermostatic element located remote from said first mentioned section, means for closing said first mentioned section, from the remaining section to effect the circulation of the fluid lengthwise of said sections, a bypass passage directly connecting said inlet with said thermostatic element, and means for regulating the amount of fluid bypassed through said passage.

In witness whereof, I hereunto subscribe my name this 19th day of April, A. D., 1923.

WILFRED SHURTLEFF
